UNITED STATES PATENT OFFICE.

MORRIS S. WRIGHT, OF WORCESTER, MASSACHUSETTS, ASSIGNOR TO M. S. WRIGHT COMPANY, OF WORCESTER, MASSACHUSETTS.

VACUUM CLEANING DEVICE.

1,184,908.

Specification of Letters Patent.

Patented May 30, 1916.

Original application filed November 17, 1909, Serial No. 528,618. Divided and this application filed April 16, 1912. Serial No. 691,206.

To all whom it may concern:

Be it known that I, MORRIS S. WRIGHT, a citizen of the United States, residing at Worcester, in the county of Worcester and State of Massachusetts, have invented certain new and useful Improvements in Vacuum Cleaning Devices, of which the following is a specification, reference being had therein to the accompanying drawing.

10 This invention relates to certain improvements in vacuum cleaning devices, and more particularly to novel and improved means for securing the dust inlet wall of the device in place and permitting ready removal

15 thereof.

The present application is a division of my application Serial No. 528618, filed November 17, 1909, entitled pneumatic cleaning machine, which said application 20 resulted in Patent No. 1,015,372, dated January 23, 1912.

In devices of the character embraced in the patent referred to, a removable wall, which constitutes the dust inlet member, is 25 provided for the vacuum chamber casing, whereby to obtain access to the interior of the casing, for emptying the collected dust, etc., and the present invention has to deal more particularly with novel means of connection for said removable dust inlet wall.

One of the objects of the invention is to overcome the use of screws and the like engaging threaded apertures in the removable wall and the wall of the casing, since 35 in such cases, when the threaded apertures become worn, it is impossible to maintain the closed contact or air-tight connection between the parts, it is necessary to bring into use a screw driver or other operating 40 tool resulting in considerable inconvenience and waste of time, and the screws are likely to become lost.

In overcoming the above and other defects, the invention herein embraces novel 45 securing means for the wall, doing away with the necessity of bringing into use any auxiliary tool, which said means is connected to one or the other of the parts comprising the vacuum chamber casing and removable wall whereby it is at all times in 50 position for use in the application of the removable wall, and when in position will uniformly maintain the parts in place, and under constant spring pressure.

Other and further improvements will be 55 appreciated from the description to follow, which for a clear understanding of the invention should be read in connection with the accompanying drawings forming a part hereof, and wherein is disclosed, for the 60 purpose of illustration a convenient and satisfactory embodiment of the invention.

In the drawings, Figure 1 is a longitudinal section of a vacuum chamber or wind chest showing one of the connecting members for the removable wall in locking engagement and the other released from engagement. Fig. 2 is a front view of the device cutaway disclosing the connecting member in locking position. Fig. 3 is a 70 side view of the device cut away and disclosing the parts in locking position.

Referring now more particularly to the drawings, wherein like reference numerals refer to corresponding parts throughout the 75 several views, a wind chest or vacuum chamber is provided, the same being designated as a whole by the reference character A, and the casing therefor comprising a bottom or base part 1, a top part 2 preferably 80 coextensive with the base part, 1, sides 3-3^a and back 4. The vacuum chamber is open at its front and is adapted to be closed by a removable front wall 5^a. This wall preferably also constitutes the front 85 wall of a removable receptacle in the form of a drawer 5, adapted to be positioned in the vacuum chamber, and has portions which overlap the wall of the vacuum chamber surrounding the opening in the 90 front thereof. The removable wall 5^a is provided with an opening, shown in the illustrated embodiment of the invention, centrally thereof, which said opening constitutes the dust inlet, and if desired, a 95 suitable coupling 5^c may be provided for the usual flexible tubing 5^b carrying a nozzle of any desired construction.

A suitable dust receiving and filtering receptacle is provided within the chamber 100 A and is indicated by the numeral 6, the same being adapted to be removably mounted on the removable wall 5^a, as more particularly brought out in the patent referred to.

Suitable means is provided for creating 105 vacuum in the chamber 1, the same preferably comprising exhausting bellows or pneu-

matics 7 of any desired construction preferably positioned on the top wall 2 of the chamber A.

The removable wall 5^a, which as before described constitutes the dust inlet member, is preferably supported and uniformly held in closed position by the following means: an elongated slot or recess is provided in the sides 3 of the vacuum chamber casing adjacent the front thereof, as shown at 41, the said recess being adapted to register each with a similar recess 42 in the sides or edges of the removable wall 5^a.

15 43 are spring members secured at one end 43^a to the sides of the chest, the said spring members being adapted to normally rest in the recesses 41 and connected at their opposite ends to pintles or bolts 44 adapted 20 to fit in the recesses 42 of said removable front wall, the pintles having a flange or head to overlie the wall of the recess 42 and terminating in an operating knob or hand piece 54.

25 It is noted that when the removable wall has been positioned, the locking pintles 44 are bodily and freely movable whereby to engage within the recesses 42 in the removable wall, the tension of the spring being 30 to exert inward pressure on the pintles thereby holding the removable wall snugly and uniformly against a suitable packing 46 interposed between said removable wall and the edges of the vacuum chamber 35 casing.

Since the locking bolts are connected to one of the parts comprising the vacuum chamber casing and removable wall, it will be observed that the same will not be accidentally displaced or lost, and are always in position for use in the application of the removable wall. In applying the removable wall, after first positioning the same on the wall of the vacuum chamber with the 45 drawer extension within the chamber, the operator takes hold of the freely movable bolts and by a swinging movement connects the same with the removable wall whereby to support the removable wall and because 50 of the fact that the securing member is lengthwise adjustable, through the medium of the spring, the removable wall will be drawn into air-tight engagement with the vacuum chamber casing, and the constant 55 spring pressure will maintain this engagement. When in locking position, the securing means since it seats within the cooperating recesses of the wall of the vacuum chamber and the removable dust inlet wall, 60 offers no obstruction beyond the sides of the device.

If desired, suitable wear plates 55 may be provided, the same being secured as by screws 56 to the outer surface of the removable wall 5^a and having slotted ways 57

adapted to register with the recesses in the edges of said removable wall, so that when the movable pintles or bolts are in locking position on the removable wall, the wall itself is protected, and will not become damaged in operation of said securing means. 70

What I claim is:

1. In a device of the character described, the combination of a box-like casing having top, bottom and side walls, one of said 75 walls being removable, and means at opposite edges of said removable wall for uniformly maintaining said side wall in tight engagement with the adjacent walls of the casing, said means including a spiral spring 80 secured at one end in a recess portion of an adjacent wall of the casing, a bolt secured to the opposite end of said spring, the removable side wall of the casing having edge recesses to receive the bolts, and said 85 bolts having a headed end to engage over the front surface of said removable wall and exerting inward pressure thereon.

2. In a device of the character described, the combination of a box like casing having 90 a bodily removable side wall, and means on the casing adjacent opposite edges of said removable side wall for uniformly holding said movable wall in position, said means including bodily removable spring held 95 bolts having an enlarged end portion to directly engage over the front surface of said removable wall, said spring being adapted to exert inward pressure on the bolt whereby the engaging portion of the latter 100 will force the removable wall into tight engagement with adjacent walls of the casing.

3. In a device of the character described, the combination of a box like casing having 105 an open side, a bodily removable closure wall for said side, said closure wall having in opposite edges recessed portions, and the adjacent side walls of the casing having aligned recessed portions, coil springs one for 110 each of said recesses and secured at one end to the casing at a point within said recesses of the casing, and bolts carried by opposite ends of said springs adapted to engage within the recesses of the removable wall and 115 having headed ends to engage over the outer surface of said removable wall.

4. In a device of the character described, the combination of a box like casing having 120 an open side, a bodily removable closure wall for said side, said closure wall having in opposite edges recessed portions, and the adjacent side walls of the casing having aligned recessed portions, coil springs one for 125 each of said recesses and secured at one end to the casing at a point within said recesses of the casing, bolts carried by opposite ends of said springs adapted to engage within the recesses of the removable wall and having headed ends to engage over the outer 130

surface of said removable wall, and metallic plates secured to the outer surface of the removable wall adjacent said recessed portions to be engaged by said headed ends of the bolts.

5. In a device of the character described, a casing having a removable wall with oppositely disposed slots in two sides thereof, spiral springs secured at one end one to 10 each of the side walls of the casing, and headed bolts secured to the outer end of said springs, the springs constituting the only supports for the bolts, whereby the latter

are adapted to bodily move in any direction, and said bolts adapted to engage in the slotted edges of the removable wall with the headed end engaging over the outer surface of said removable wall, whereby to maintain the latter under spring pressure in contact with the adjacent walls of the casing. 15

In testimony whereof I affix my signature in presence of two witnesses.

MORRIS S. WRIGHT.
